UNITED STATES PATENT OFFICE

2,667,446

MANUFACTURE OF HIGH OCTANE
GASOLINERobert A. Findlay, Bartlesville, Okla., assignor to
Phillips Petroleum Company, a corporation of
Delaware

Application September 25, 1950, Serial No. 186,523

3 Claims. (Cl. 196—14.26)

1

This invention relates to a process for the manufacture of high octane gasoline by treatment of ordinary gasolines such as straight run gasolines, natural gasolines. Such gasolines are known to boil substantially throughout the approximate range of 90° F.—400° F., which is the usual gasoline boiling range. In one of its aspects the invention relates to the solvent extraction of a gasoline with a solvent and under conditions such as to obtain from said gasoline certain highly desired components thereof which may then be used as such or blended with other materials to form a final gasoline product having high octane rating or value. In another of its aspects the invention relates to a solvent extraction process for the treatment of a gasoline wherein a single solvent is employed in a manner such as to allow its use in both stages of a two stage solvent extraction of a gasoline to separate the said gasoline into fractions which can be as follows:

1. A highly aromatic fraction containing light naphthalenes,
2. A highly paraffinic fraction containing 7 carbon atoms and higher paraffins,
3. A hexane concentrate which will contain neo-hexane which can be recovered therefrom as a very highly desirable component and
4. A highly naphthenic concentrate or fraction boiling above about 220° F.

According to this invention it has been found possible to manufacture a high octane gasoline by solvent extraction with a suitable solvent, for example, furfural, provided said solvent is employed in at least a two stage operation or process. Thus, it has been found that it is possible to first treat a gasoline with for example furfural by solvent extraction to obtain an extract phase containing the lighter naphthalenes and most of the aromatics originally present in said gasoline and a raffinate phase containing heavy naphthalenes and paraffins and to then separate from said raffinate by solvent extraction with for example furfural the said heavier naphthalenes and light paraffins following which the highly desirable light paraffins can be separated from the heavy naphthalenes by conventional distillation or fractionation.

Preferably the gasoline treated according to the invention is depentanized before the solvent extraction steps are practiced.

Therefore, in its preferred form the process of this invention comprises the steps in combination and in the order as follows:

- (a) Depentanizing a gasoline;
- (b) Subjecting said depentanized gasoline to

2

solvent extraction with a solvent and under conditions suitable to form an extract phase containing the lighter naphthalenes and most of the aromatics originally present in said gasoline and a raffinate phase containing heavier naphthalenes and paraffins originally present in said gasoline;

- (c) Recovering separately from said extract phase the lighter naphthalenes and aromatics, on the one hand, and solvent, on the other;
- (d) Subjecting said raffinate to solvent extraction with said recovered solvent and under conditions suitable to form a second extract phase containing heavier naphthalenes and light paraffins and a second raffinate phase; and
- (e) Recovering separately from said second extract phase a light paraffin concentrate, heavier naphthalenes and solvent.

In order to more fully illustrate the concept and process of this invention reference is made to the drawing in which a gasoline supplied through line 1 to a fractionator 2 is depentanized in said fractionator, the pentanes and any lighter materials being removed from fractionator 2 through line 3, and the depentanized gasoline is passed through line 4 into solvent extractor 5. Solvent is introduced into the top of extractor 5 through line 6 wherein a first raffinate containing heavier naphthalenes and paraffins is formed and taken off through line 7 while solvent containing light naphthalenes (boiling 120—220° F.) and most of the aromatics is withdrawn as the extract phase from the bottom of said extractor through line 8. The first raffinate is passed through line 7 to extractor 9. The extract phase withdrawn from extractor 5 through line 8 passes to fractionator 10 in which aromatics and light naphthalenes are removed as overhead through lines 11 and 12. Some of this overhead is used as a reflux for extractor 5 and is passed thereto through line 13. Hot solvent from the bottom of fractionator 10 is removed through line 14 and passed to extractor 9 wherein it is employed to produce a second raffinate, which is passed to a solvent recovery system, through line 15 and a second extract phase which is passed through line 16 to a fractionator 17 wherein a hexane concentrate, a heavy naphthalenes concentrate (boiling 220—320° F.) and solvent are removed through lines 18, 19 and 20, respectively. Heavier naphthalenes are used as reflux for extractor 9 and to this end are passed thereto through line 21. Obviously, the extractors 5 and 9 are filled with liquid moving in counter-current directions and the so called refluxing thereof is effected at the bottoms thereof.

The temperatures in extractors 5 and 9 are

usually in the ranges 80-110° F. and 150-200° F., respectively, preferably in the ranges 90-100° F. and 160-180° F., respectively. It is possible, by employing a greater ratio of solvent to hydrocarbon in the second extractor than is employed in the first extractor, to operate both extractors at substantially the same temperature.

It is now obvious that the invention provides a unitary and highly economical as well as very practical process for the preparation of a very desirable gasoline component and indeed by suitably operating the system it is possible to extract the lightest hexanes, for example neohexane into the first extract if desired, although this is not now preferred. The final solvent recovery step can be an extraction by pentane followed by fractionation if needed or desired. Thus, in the event that the extracted hydrocarbons boil close to furfural, or form azeotropes with it, a pentane extraction, as described, can be practiced.

Equivalent solvents as well as equivalent steps falling within the scope of the claims appended hereto obviously will be within the scope of one skilled in the art in possession of this disclosure.

The drawing which is a flow plan of but one form of apparatus arrangement suitable for effecting the process of this invention is schematic only. Accessories such as pumps, temperature indicators, etc. have been omitted for sake of simplicity. Supply of omitted parts of the apparatus as well as process conditions required to place the invention into use will be within the skill of the art in possession of this disclosure.

I claim:

1. In the manufacture of a high octane gasoline from a gasoline selected from the group consisting of straight-run and natural gasoline the steps which comprise in combination, and in the order as follows, (a) depentanizing one of said gasolines boiling substantially throughout the approximate range of 90°-400° F. (gasoline boiling range), said gasoline containing substantial proportions of light and heavy naphthenes, light and heavy paraffins, aromatics and including hexanes; (b) subjecting said depentanized gasoline to a solvent extraction with a solvent and

under conditions causing formation of an extract phase containing said light naphthenes and substantially all of said aromatics, and a raffinate phase containing said heavy naphthenes and said light and heavy paraffins; (c) recovering separately from said extract phase an aromatics and light naphthenes fraction on the one hand and solvent on the other; (d) subjecting said raffinate (obtained in step (b) hereof) to solvent extraction with said recovered solvent and under conditions causing formation of a second extract phase containing heavy naphthenes and light paraffins and a second raffinate phase; and (e) recovering separately from said second extract phase a light paraffin concentrate containing hexanes, a heavy naphthenes concentrate and solvent.

2. A manufacture according to claim 1 wherein the solvent is furfural, the first solvent extraction is effected at a temperature in the range 80°-110° F., the extract phase contains light naphthenes boiling in the range 120°-220° F. and substantially all of any aromatics originally present in said gasoline and wherein the second extraction is effected at a temperature of 150-200° F. and the extract phase contains heavy naphthenes boiling in the range 220°-320° F.

3. The process of claim 1 wherein the hexanes are separately recovered and blended with a gasoline whose octane value is to be improved.

ROBERT A. FINDLAY.
